UNITED STATES PATENT OFFICE.

LEWIS R. MOORE, OF ELKHART, INDIANA.

FOLDING TABLE.

Application filed November 7, 1924. Serial No. 748,480.

This invention relates to improvements in tables, especially folding tables.

An object of this invention is to provide an improved folding table having an improved leg hinge in which the leg is automatically latched in the erected, or operative, position, and in which no lateral braces of any kind are required. Another object of this invention is to provide a folding table 10 having an improved leg hinge which not only enables automatic latching of the leg in the erected position but also constitutes a part of the table frame. Other objects of the invention are mentioned and described 15 herein.

The preferred embodiment of this invention is illustrated in the accompanying drawing, in which Figure 1 is a top plan view of my improved folding table; Fig. 2 20 is a section in fragment taken on line 2—2 of Fig. 1 illustrating a table leg in the inoperative or folded position; Fig. 3 is a similar view showing the leg in the erected position and the hinge in section; Fig. 4 is 25 a fragmental view illustrating a leg top and a hinge enlarged and in elevation; Fig. 5 is a section taken on the line 5—5 of Fig. 4; and Fig. 6 is a bottom plan view of a leg hinge.

On the drawings, similar numerals of reference indicate like parts throughout the several views thereon.

Referring to the details of the drawing the numeral 1 indicates the outside rectangular frame section of a table which may comprise four rails of wood suitably joined together at their ends, and the numerals 2, 2 indicate the inside rectangular frame element composed of four wood rails 2, 2 suitably secured together at their ends and to frame elements 1, and also secured together by the metal leg hinge, as hereinafter described.

The upper face of the inside frame rails 2 45 may be disposed in a plane somewhat lower than the upper face or edge of frame section 1 and is adapted to carry the thin table top 3, made of wood or other suitable material, which may be secured thereto by screws, or otherwise in any suitable manner, not shown. The table top 3 may be overlaid by a cover 4, of leather or other suitable material, the marginal edges thereof may be gripped between frames 1 and 2. The upper 50 edge of each rail of outside frame 1 may be somewhat rounded or convexed, in cross sec-

tion, and may be covered with a strip 5 of felt, or other suitable fabric, which strip may have its inside marginal edge rigidly gripped between the rails of the frame sections 1 and 2, and its outside marginal edge may be secured to the outside face of frame 1 by the fastener strips 6 which may be secured to frame 1 in any suitable manner. Angular metal corner pieces 7 may be fastened to the table frame at each corner thereof in any suitable manner.

The table may be provided with four folding legs 8, one only being shown, at the corners thereof, said legs being pivotally connected with the table frame by a hinge.

Inasmuch as all legs and hinges, respectively, are alike only one of each is illustrated in the drawing. The hinge element 9 is preferably formed of sheet metal stamping in one piece and comprises main U-shaped section which includes the parallel side walls 10 and 11, the fastener extension 12 integral with side wall 11, and the substantially L-shaped extension 13 formed on the end of the hinge web 14.

The wall 11 and extension 12 of the hinge are arranged against the inside side wall of a rail of frame 2 and may be rigidly secured thereto by a screw 15 which engages through

the screw aperture 16 formed in hinge section 12, and the L-shaped hinge element 13 has its lower leg disposed beneath the end of another rail of frame 2 and rigidly secured thereto by a screw 17 engaging

through the aperture 18 therein. In this structure it should be noted that where the frame section 2 is composed of four wood rails arranged rectangularly, said frame rails are rigidly tied together by the hinge element 9 which really constitutes a member of the table frame when secured therein as described, thereby effecting a very rigid and durable table frame structure.

The hinge element 13 has its upright leg 100 formed somewhat inclined and curved at its lower end to provide a cam face 19 thereon, an aperture 20 being formed in said leg to receive the table leg latching means, as hereinafter described. The upper end of each leg 8 is pivotally mounted upon the hinge pin 21 which is disposed transversely of and has its ends rigidly secured in walls 10 and 11 of the hinge 9, whereby each leg may be folded or swung to the collapsed position 105 beneath the table top parallel with a rail of frame section 2 (Fig. 2) or to the erected po-

sition thereof (Figures 3 and 4). For releasably latching the leg 8 in the erected position (Fig. 3) a bent spring arm 22 is secured to the leg at 23 extending longitudinally thereof, said arm having its free end disposed adjacent the top end of the leg. A latching stud 24 is rigidly secured to the arm 22 adjacent its upper free end and projects angularly therefrom, the upper extremity of said arm being inwardly bent at 25 to form a yieldable cam element adapted to engage the cam face 19 of the hinge extension 13.

In operation, and when it is desired to use the table, the legs 8 are swung from the collapsed position to the erected position in which movement the cam element 25 of the arm 22 first engages stationary cam 19, thereby depressing the arm 22 inwardly and causing the stud 24 to slide along the inner face of the upright leg of hinge element 13 until it reaches the aperture 20 with which it registers and immediately engages automatically by virtue of the springy quality of the arm 22, thereby rigidly latching the table leg in the erected position, in which position it is held without the use of braces of any character. Manual depression of the arm 22 readily disengages the stud 24 from the socket 20, whereby the table leg may be quickly restored to the collapsed position beneath the table top.

The incorporation of the felt strip 5, which may be slightly elevated in relation to the top 3, is very advantageous in preventing easy displacement of playing cards from the table top when the table is used as a card table, for the strip offers considerable resistance thereto, a much greater resistance than a leather or wood table top would.

I claim:—

1. The combination with a frame, of a stationary channelled hinge element mounted upon said frame, the web of said hinge element being provided with an angular ex-

tension which forms a combined cam element and keeper, a leg pivoted to said hinge element, a resilient compressible latching arm mounted upon said leg and movable therewith, and means for latching said leg to said keeper, said means including a complementary stud and recess connection between said arm and keeper, said means being effected by movement of said arm into engagement with the cam section of said combined cam and keeper. 55

2. The combination with a frame, of a stationary channelled hinge element mounted upon said frame, the web of said hinge being provided with an angular downwardly extending extension which forms a combined cam element and keeper, a leg pivoted within the channel of said hinge, a resilient compressible latching arm mounted upon said leg and movable therewith, and means for latching said leg to said keeper, said means including a stud carried by said arm and a recess formed in said keeper, said means being effected by movement of said arm into engagement with the cam section of said combined cam and keeper. 60

3. The combination with a frame, of a stationary channelled hinge element mounted upon said frame, the web of said hinge being provided with an integral downwardly projecting extension which forms a combined cam element and keeper, a fastener extension connected with said combined cam and keeper, a leg pivoted within the channel of said hinge, a resilient compressible latching arm mounted upon said leg and movable therewith, and means for latching said leg to said keeper, said means including a complementary stud and recess connection between said arm and keeper, said connection being effected by movement of said arm into engagement with said cam section of the combined cam and keeper. 65

In testimony whereof I affix my signature 70 this 4th day of November, 1924.

LEWIS R. MOORE.
